UNITED STATES PATENT OFFICE.

SYLVESTER S. MARVIN, OF PITTSBURG, PENNSYLVANIA.

DESIGN FOR A CHOCOLATE COMFIT.

40,269.

Specification for Design. Patented Sept. 21, 1909.

Application filed June 5, 1909. Serial No. 500,441. Term of patent 14 years.

To all whom it may concern:

Be it known that I, SYLVESTER S. MARVIN, a citizen of the United States, residing in the city of Pittsburg, in the county of Allegheny and State of Pennsylvania, have invented a new, original, and ornamental Design for Chocolate Comfits, of which the following is a specification, reference being had to the accompanying drawing, forming part thereof.

In the drawing Figure 1 is a side elevation and Fig. 2 is an end elevation showing my new design.

I claim:

The ornamental design for chocolate comfits, as shown.

SYLVESTER S. MARVIN.
